UNITED STATES PATENT OFFICE.

CHARLES B. COATES, OF CHICAGO, ILLINOIS, ASSIGNOR TO CHICAGO PNEUMATIC TOOL COMPANY, OF CHICAGO, ILLINOIS, A CORPORATION OF NEW JERSEY.

TRACK-DRILLING MACHINE.

1,118,268.

Specification of Letters Patent. Patented Nov. 24, 1914.

Application filed September 17, 1912. Serial No. 720,757.

To all whom it may concern:

Be it known that I, CHARLES B. COATES, a citizen of the United States, residing at Chicago, in the county of Cook and State of Illinois, have invented certain new and useful Improvements in Track-Drilling Machines, of which the following is a specification.

My invention relates to what are known as track drilling machines, particularly adapted and arranged for drilling tie or joint holes, reaming joint holes, and also for drilling holes for rail bonding, although I contemplate using my invention wherever applicable.

The object of my invention is to provide a simple and efficient machine of this character built for rapid work and adapted to be applied to and removed from the track in a simple and rapid manner, being provided with means for feeding the drill to the work and also for moving and adjusting the drill to different positions so as to drill at different heights.

The various features of advantage and utility in my construction of machine will be apparent from the description herein-after given.

In the drawings Figure 1 is a perspective of my machine shown in connection with and applied to a track; Fig. 2 an end elevation thereof looking from the inside of one of the rails, that is, with the right-hand rail in Fig. 1 omitted; Fig. 3 a section on the line 3—3 of Fig. 4 with a portion thereof broken away; Fig. 4 a plan view of the machine; Fig. 5 a side elevation thereof; Fig. 6 an end view of the guide rods extending transversely of the track; Fig. 7 a detail view of the feed screw construction, the same being a horizontal section on the line 7—7 of Fig. 8; Fig. 8 a vertical section on the line 8—8 of Fig. 7; Fig. 9 a detail view of a modified form of construction of hook for one end of said guide rods; Fig. 10 a plan view illustrating a clamp that may be used for the other end of the guide rods; Fig. 11 a vertical section on the line 11—11 of Fig. 10; and Fig. 12 an end view of the parts shown in Figs. 10 and 11.

Referring to the present embodiment of my machine as shown in the drawings, the same comprises two essential parts, the drill motor and its drill and the supporting and guiding structure therefor, which by

preference are made detachable in the manner hereinafter explained in order that the drill motor may be, if desired, used for other purposes as an independent portable tool. The drill motor, which is indicated in general by the reference character 1, may be of any desired construction and character and may be operated by electricity, compressed air or the like, as usual, for which reason illustration and description of its mechanism are unnecessary.

To the casing of the drill motor is secured in suitable manner as by means of the screws 2^a an inverted yoke 2 encompassing the upper portion of the casing or body of the drill motor and provided on each side with a pair of vertical guide ribs 3. It will be understood that the drill motor is provided with a suitable drill or bit shown at 4.

The supporting and guiding structure for the drill comprises a pair of similar right and left hand frames each consisting of a tubular portion 5 and a pair of vertical guides 6 with which the guide ribs 3 cooperate for vertical adjustment of the drill 70 motor and drill. These tubular portions 5 are fitted to and slide upon a pair of parallel rods 7 in the operation hereinafter described of the movement of the drill to the work. The frames are also provided with vertical portions 8 which are connected at their top by means of a cross piece or bar 9 secured thereto by the screws 9^a and having a central opening. Within this opening is rotatably mounted a feed nut 10 constituting the tubular portion or hub of a hand operating wheel 11. This nut is held in place by means of the clamping ring 12 and set screw 13 (Figs. 2 and 3). This feed nut engages the vertical feed screw 14 which is secured at its lower end to the top side of the drill casing with the result that when the adjusting wheel 11 is rotated in one direction or the other, the entire drill structure is raised or lowered accordingly.

At the same time this adjusting mechanism constitutes the means for supporting the drill within the frames described. The tubular portions 5 of these frames are connected by a cross piece or yoke 15 from which projects centrally thereof the feed screw 16. While the two frames, including the portions 5 and the guides, may be made integral with the yoke 15, I prefer to make them separate as shown to facilitate the

work of manufacture. This screw 16 passes through the threaded central portion of a cross bar 17 whose ends are tubular so as to fit upon the guide rods 7. This cross bar 17 is adapted to be held in different adjusted positions along the length of these rods, and for this purpose these rods have a series of vertical holes 7^a at intervals and each of the tubular ends of the cross bar 17 5 has a corresponding hole through each of which passes a pin 18 whereby such cross bar is held in any desired position along the length of the rods. The adjusting screw 16 is provided with a hand wheel 19 10 for operating the same. It will be understood that by turning this wheel in one direction or the other the drill motor and its immediate supporting frames are moved toward or away from the work according to 15 20 the direction of rotation of the wheel.

In practice I prefer to attach the feed screw 16 to the yoke 15 in the manner shown in detail in Fig. 7, according to which the central part of the yoke is bored to receive 25 the extended reduced end 16^a of the feed screw, which is provided with a circumferential groove 16^b. The free ends of a looped wire or rod 16^c pass through holes in the yoke and engage said groove, whereby the 30 parts are securely but detachably held together.

That end of the rods 7 adjacent the rail to be drilled is provided with a connecting or cross bar 20 having socketed ends 20^a to 35 receive said rods, the parts being held together in suitable manner as by means of the set screw 21. In addition each end of this cross bar 20 is provided with a depending portion 22 which is adapted to hook 40 over the particular rail of the track being operated upon (Figs. 5 and 6). The other ends of the rods 7 are connected by means of the cross bar 23 having tubular end portions 23^a fitting upon said rods and secured there- 45 to in suitable manner as by means of the set screws 24. These particular ends of the rods rest upon the track which is not being operated upon and according to my particular construction now being described the ma- 50 chine is held in place upon the track at this end by the weight of the operator who sits upon the seat 25 secured near said end of the rod 7 in suitable manner and in rear of the drill motor, advantage being taken of 55 the fact that the operator would naturally sit down at this point in the performance of his work. As shown, the seat is provided with depending straps 26 upon the rod 7. The location of the seat corresponds to the 60 most convenient one for the operator in operating the feed of the drill.

In operation the machine is applied to the track by hooking over the proper ends of the rods 7 upon the rail to be drilled and 65 resting the other ends of the rods upon the

other rail. The drill is then adjusted vertically if necessary for the proper height or position of the hole and the drill started and fed to the work by operation of the hand wheel 19, it being understood that the operator sits upon the seat 25 and keeps the machine down in place upon the track. After the hole is drilled, the drill or bit can be withdrawn by turning the feed wheel in the reverse direction, or, if desired, the pins 18 can be removed and the drill and its supporting frames rapidly withdrawn by sliding them upon the rods 7. 70

When the rails are sufficiently secured in place on the road bed so that they will not tip when operated upon by the drilling machine it is sufficient to use the comparatively short hooks 22 hereinbefore described, but there are instances where it is desired to drill rails which are not yet secured in position, with the result that when the drilling machine has these short hooks there is a liability of tipping of the rail when operated upon. To meet this contingency I provide the elongated hooks 22^a, as shown in Fig. 9, 90 the same having a vertical portion extending downwardly parallel with the web of the rail and a horizontal inturned portion adapted to contact such web at a point approximating the middle portion thereof as 95 to height, so that any tendency of the rail to tip or cant is effectually overcome.

While it may be sufficient, as hereinbefore described, to merely rest one end of the guide rods upon the rail not being drilled 100 and to have the operator sit upon the seat provided, if desired means may be provided for clamping such end of the rods to said rail, such means to be employed with or without the seat or equivalent device, as 105 may be preferred. I have shown in Figs. 10 to 12 a desirable clamping means of this character. As shown, I extend the guide rods some distance beyond the rail not being drilled and fit thereupon a cross piece 110 or bar 27 having tubular ends 27^a which slidably fit upon said rods and are secured thereto in suitable manner, as by means of the set screws 28. In advance of this cross bar 115 I provide on said rods a cross bar 29 which is similar, with the exception that the same is adapted to freely slide upon the rods, and is not adapted to be secured thereto in any adjusted position, as is the case with the cross bar 27. This cross bar 29 is 120 held toward the cross bar 27 with a yielding pressure as by means of the coil springs 20. The cross bar 29 is provided toward its ends at a point adjacent its tubular portions 29^a with depending angular hooks or fingers 125 29^b which extend toward the rail and are adapted to engage the same, as clearly shown in Fig. 11. In order to project said hooks to clamping position and to hold them in such position, suitable means may be em- 130

ployed, such as the circular cam 31 pivotally mounted at 32 between the two bearing lugs 27^b of the cross bar 27. This cam is provided with an operating lever 33 secured thereto at its lower end, with the result that when the lever is operated it rotates and forces the cam 31 against the intermediate horizontal portion of the cross bar 29, so that the clamping hooks 29^b are forced against and retained in engagement with the rail, as described. The proper engagement of these hooks with a different character of rail is obtained by adjusting the cross bar 27 to the proper position on the guide rods.

It is evident that both ends of the supporting and guiding rods 7 are connected together by cross bars 20 and 23 each terminating in sleeves 20^a and 23^a secured to said rods. Each of these sleeves is provided with a depending boss which is flat on its lower face so as to rest flatly and firmly upon the top face of the rails as shown more clearly in Fig. 5 wherein the sleeve 20^a is shown provided with bosses 20^b and the sleeve 23^a with bosses 23^b. In this manner perfect alinement of the drilling machine can be obtained and the drill caused to drill perfectly at right angles through the web of the rail and moreover these flat bosses give a solid and firm bearing upon the rails for the supporting rods.

As hereinbefore stated, any particular construction and type of drill motor may be employed, but in the present instance the same is of a type operated by electricity, which is desirable when the machine is being employed on traction roads where a supply of electricity is available from the trolley wire. Consequently I have shown in some of the figures of the drawings the electric supply cable 34 extending into the drill motor, in the present instance the same passing centrally through the feed screw 14.

55 The drill motor may be removed from the supporting frame by removing the four screws 9^a and turning the bar 9 a quarter turn, after which the drill motor is free to be slipped downwardly or permitted to drop from the frame, or, if desired, the feed nut 10 may be turned until the adjusting screw 14 is disengaged therefrom.

As clearly shown in the drawings the construction and arrangement of the parts is such that the center of gravity of the drill and frame is below the top line or plane of the rail which not only facilitates the handling of the machine but also materially improves its action. The greater portion of the machine is suspended from and arranged below the guide rods 7 and whether the drilling machine proper is at its highest position or not the center of gravity is not above the top plane of the rail. Furthermore I have so constructed my machine that

I am enabled to bore holes at the lowest possible point in the web of the rail without any interference between the drill body and a tie for instance, the lower portion of the drill body being free of all parts that would otherwise interfere with this capability.

I claim:

1. A track drilling machine comprising a drill motor and its drill, a frame for supporting and guiding the drill motor and adapted to be supported upon the track, the center of gravity of the motor and frame being at or below the top line of the rail, and means for feeding the drill motor and drill to the work.

2. A track drilling machine comprising a drill motor and its drill, a supporting and guiding structure including rods adapted to rest upon and of a length to span the two rails of the track, and guide frames slidable on said rods and supporting the drill motor, the center of gravity of the motor and frame being at or below the top line of the rail, and means for feeding the drill motor to the work.

3. A track drilling machine comprising a drill motor and its drill, a supporting and guiding structure comprising rods adapted to be supported by the track and guide frames slidable on said rods and supporting the drill motor, a cross bar secured between the rods, and a feed screw coöperating with the bar and the frames for feeding the latter and the drill motor to the work.

4. A track drilling machine comprising a drill motor and its drill, a supporting and guiding structure comprising rods adapted to be supported by the track and guide frames slidable on said rods and supporting the drill motor, a cross bar secured to and arranged between the rods, and a feed screw coöperating with the bar and the frames for feeding the latter and the drill motor to the work, said rods having means at one end for engaging a rail of the track.

5. A track drilling machine comprising a drill motor and its drill, a supporting and guiding structure comprising rods adapted to engage the track and guide frames slidable on said rods and supporting the drill motor, a cross bar secured to and arranged between the rods and a feed screw coöperating with the bar and the frames for feeding the latter and the drill motor and its drill to the work, said bar being adjustable to different positions on the rods.

6. A track drilling machine comprising a drill motor and its drill, a supporting and guiding structure comprising rods adapted to engage the track and guide frames slidable on said rods and supporting the drill motor, a cross bar having tubular ends fitted to slide upon the rods, said rods having along their length a series of holes, pins for securing the bar to the rods at different po-

sitions thereon, and a feed screw coöperating with the bar and with the frames for feeding the latter and the drill motor and drill to the work.

5. 7. A track drilling machine comprising a drill motor and its drill, a supporting and guiding structure comprising rods adapted to engage the track and guide frames slideable on said rods and supporting the drill 65 motor, a yoke connecting the frames, a cross bar secured between the rods and having a central feed screw opening, and a feed screw passing through said screw opening and engaging the yoke for feeding the frames 10 and the drill motor and drill to the work.

8. A track drilling machine comprising a drill motor and its drill, a supporting and guiding structure comprising rods adapted to be supported by the track and guide 70

20 frames slideable on said rods and supporting the drill motor, a platform arranged upon the rods and in rear of the drill motor and adapted to receive a removable weight, and means for feeding the drill motor to the 25 work, the drill being suspended from the rods with its center of gravity below the plane of said rods.

9. A track drilling machine comprising a drill motor and its drill, a supporting and 30 guiding structure comprising rods and guide frames slideable on said rods and supporting the drill motor, said rods having one end formed to hook over a rail of the track, a platform secured to the rods near 35 their other ends and adapted to receive a removable weight, and means for feeding the drill motor and drill to the work, the drill being suspended from the rods with its center of gravity below the plane of 40 said rods.

10. A track drilling machine comprising a drill motor and its drill, a supporting and guiding structure comprising rods adapted to engage the track and guide frames slideable on said rods and supporting the drill 45 motor, said frames and drill motor having coöperating guiding means, an adjusting screw coöperating with the frames and drill for adjusting the position of the drill, and 50 means for feeding the drill motor and drill to the work.

11. A track drilling machine comprising a drill motor and its drill, a supporting and guiding structure comprising rods adapted 55 to engage the track and guide frames slideable on said rods and supporting the drill motor, said drill motor having a casing provided on each side with a pair of vertical 60 guide ribs, and said frames being each provided with two vertical channels receiving

said ribs, and means for feeding the drill motor and drill to the work including a cross bar connecting said frames and provided with a central opening, a feed nut 65 therein, and a feed screw secured to the drill motor and engaged by the nut.

12. A track drilling machine comprising a drill motor and its drill, a supporting and guiding structure comprising rods adapted to engage the track and guide frames slideable on said rods and supporting the drill 70 motor, a yoke connecting the frames, a cross bar secured between the rods and having a central feed screw opening, and a feed screw passing through said screw opening and 75 engaging the yoke for feeding the frames and the drill motor and drill to the work, said screw being removably secured to said yoke.

13. A track drilling machine comprising 80 a drill motor and its drill, a supporting and guiding structure comprising rods adapted to engage the track and guide frames slideable on said rods and supporting the drill motor, a yoke connecting the frames and 85 having a central opening, a feed screw having an unthreaded end received by said opening, means for securing such end therein, and a cross bar secured between the rods and having a central opening for the feed 90 screw.

14. A track drilling machine comprising a drill motor and its drill, a supporting and guiding structure therefor, including rods 95 adapted to rest upon and span the two rails of the track, means at one end of the rods for engaging a rail, and clamping mechanism at the other end of the rods for engaging the other rail comprising a movable clamping finger slideable on the rods and 100 adapted to engage the rail, and a manually operated device for operating the same.

15. A track drilling machine comprising a drill motor and its drill, a supporting and guiding structure therefor, including rods 105 adapted to rest upon and span the two rails of the track, means at one end of the rods for engaging a rail and clamping mechanism at the other end of the rods for engaging the other rail comprising a cross bar slideable on said rods and having a clamping finger adapted to engage the rail, a second cross bar secured to the rods, and a cam mounted on the latter bar and adapted to contact the first bar and force its finger 110 against the rail.
